FOG TYPE INSULATOR

Joseph T. Lusignan, Jr., Mansfield, Ohio, assignor to The Ohio Brass Company, Mansfield, Ohio, a corporation of New Jersey

Original application June 2, 1934, Serial No. 728,711. Divided and this application January 18, 1935, Serial No. 2,363

6 Claims. (Cl. 173—318)

This invention relates to electric insulators and particularly to high potential insulators for use under adverse atmospheric conditions, such as those encountered with a fog, dust, smoke, or other contaminating substances present in the atmosphere.

One object of the invention is to provide an insulator which will operate satisfactorily under such adverse conditions.

10 Another object of the invention is to provide an insulator that will not produce radio disturbances when subjected to fog or other moisture in the air.

15 Another object of the invention is to provide an insulator which shall be of improved construction and operation.

Other objects and advantages will appear from the following description.

The invention is exemplified by the combination and arrangement of parts shown in the accompanying drawing and described in the following specification, and it is more particularly pointed out in the appended claims.

The present application is a division of my 25 prior application Serial Number 728,711, filed June 2, 1934.

In the drawing the figure is an elevation with parts in section showing one embodiment of the present invention.

30 There are a number of factors which enter into the design of an insulator, contributing to its successful operation under adverse atmospheric conditions, such as are encountered where fog, dust, smoke and other contaminating substances are present in the atmosphere. One desirable characteristic of such an insulator is that it shall have a large surface leakage distance and surface resistance. This may be obtained by the use of deep petticoats, corrugations, multipart surfaces, etc. It is also desirable that at least a portion of the leakage surface shall be sheltered to prevent accumulation of deposits upon these surfaces which would tend to decrease their leakage resistance. It is also 35 desirable that a portion of the leakage surface shall be exposed so that it may be automatically cleaned by rain. This cleaning will be more effective if the exposed surface is free from inequalities and shaped so as to be least liable 40 to collect and retain foreign material. The present invention provides surfaces which, to a large degree, are protected from the accumulation of fog, dust and other contamination, and other surfaces which are adapted for automatic 45 cleaning, thus taking advantage of the characteristics of both kinds of surfaces.

In the form of the invention shown in the figure, the numeral 10 designates a member of porcelain or other suitable dielectric material 50 provided with a cap 11 and a pin 12. The cap

11 and pin 12 are secured to the dielectric member by means of cement 13. The dielectric member is provided with an ample flange or petticoat 14 which extends outwardly and is curved downwardly to form a canopy enclosing the pin 5 12 and providing a sheltered space of considerable extent surrounding the pin. Skirts 15 and 16 extend downwardly from the lower surface of the flange 14 to provide increased leakage surface in the sheltered space beneath the flange. 10 In order further to protect the lower surface of the flange 14 from contamination, a baffle 17 is supported by the pin 12 and is provided with an upwardly opening channel shaped portion which registers with the skirt 16 and into which 15 the lower edge of the skirt extends. The outer edge of the baffle 17 extends upwardly into the circumferential channel between the skirts 15 and 16. In this way, overlapping baffles are provided which will break up any eddy currents 20 beneath the canopy 14 and effectually protect the inner portion of the lower edge of the dielectric member from contamination, either by fog or dust particles in the air. The baffle 17 may be made of thin metal or dielectric material, and since it is spaced away from the lower edge of the dielectric member 14, it does not materially reduce the insulation even when made of metal. It may be detachably secured to the pin 12 by means of a nut 18 so that it may be 25 removed for purpose of inspection or for cleaning if necessary. The recess in the baffle 17 is provided with one or more openings 19 to permit any moisture that may collect within the recess to drain away. Cover plates 20 are disposed over the openings 19 to intercept any currents of air which might otherwise pass upwardly through the openings 19. Any suitable form of baffle may be used for the cover plates 20 which will intercept air currents through the 30 openings 19 but will permit drainage of moisture from the upper face of the baffle 17. The baffle 17 is set well up in the enclosed space beneath the flange 14 so that there is little tendency for eddy currents of air to follow the labyrinthine path between the skirts 15 and 16 and the baffle 17. This keeps the lower face of the dielectric member 10 dry at all times, and especially that portion of the face inside of the skirt 16. 35

The wall of the recess in the dielectric member at the termination of the cement is given a coating of conducting material 35. This conducting material may be a metal coating sprayed onto the surface of the porcelain or may be any 40 other form of conducting covering and extends along the surface of the dielectric a sufficient distance to form good electrical contact with the cement and extends beyond the termination of the cement for a short distance, usually approxi- 45 50 55 60

mately one-quarter of an inch. The coating band may be easily applied by a spray gun or other suitable means without interfering with the regular method of assembling the insulator pin in its recess. The purpose of this conducting zone is to prevent discharge across the air space between the pin and porcelain where the electrostatic field is concentrated. Since the cement is relatively conducting, the air space between the pin and the porcelain adjacent the termination of the cement is short-circuited by the cement and conducting covering 35, thus preventing difference of potential between the pin and the surface of the porcelain, such as would otherwise cause discharge across this space and consequent radio disturbance.

In the invention shown, a dielectric member is provided having an outwardly and downwardly extending flange providing a canopy, on the lower face of which is formed a downwardly extending skirt cooperating with a baffle disposed entirely within the space enclosed by the canopy and providing a labyrinthine passage which prevents eddy currents of air from depositing moisture or other contamination on the inner face of the skirt and the lower face of the dielectric member within the skirt. By thus protecting the surface of the dielectric member adjacent the pin, the chief source of radio disturbance is overcome. Where the dielectric member adjacent the pin is exposed to moisture, discharges are apt to emanate from the pin out over the surrounding surface, thus giving rise to radio disturbances. This is, of course, aggravated by the presence of dust or other foreign matter on the surface of the insulator about the pin. The embodiment shown also provides an extensive, smooth outer face which is easily washed by rain and thus kept clean. In this way, effective insulation is provided for all weather, even under the most adverse conditions.

I claim:

1. An insulator comprising a dielectric member having an outwardly extending downwardly curved flange, a downwardly extending petticoat on the lower face of said flange, a fitting extending downwardly from said insulator, a sheet metal disc of conducting material carried by said fitting and electrically connected therewith and extending outwardly from said fitting beneath said flange and having a circumferential groove in the upper face thereof registering with said petticoat, said disc serving both as a baffle for protecting the surface of said insulator from contamination and also as a flux control to prevent concentration of electrostatic flux and electrical discharge from said pin.

2. An insulator comprising a dielectric member having an outwardly extending downwardly curved flange, a downwardly extending petticoat on the lower face of said flange, a fitting extending downwardly from said insulator, a baffle carried by said fitting and extending outwardly beneath said flange and having a circumferential groove in the upper face thereof registering with said petticoat, an open drain for said groove extending through said baffle, and a cover for said drain but spaced therefrom for intercepting air currents passing through said open drain.

3. An insulator comprising a dielectric member having a recess in the lower face thereof, a fitting secured to the upper face of said insulator, a pin secured in said recess and extending down-

wardly therefrom, an outwardly extending flange on said dielectric member, the outer portion of said flange being curved downwardly, a petticoat extending downwardly from the lower face of said flange, a sheet metal baffle carried by said pin and extending outwardly beneath said flange and serving as a flux control to diffuse the electrostatic lines of force emanating from said pin, said baffle being disposed entirely above the plane of the lower edge of said flange and having a circumferential groove in its upper face registering with said petticoat and forming with said petticoat a labyrinthine passage to protect the surface of said insulator from contamination, and means for detachably securing said baffle to 15 said pin.

4. An insulator comprising a dielectric member having a recess therein, a pin having one end thereof secured in said recess, a cap secured to said dielectric member for supporting said insulator, an outwardly and downwardly extending flange on said dielectric member enclosing a sheltered space about the lower end of said pin, said dielectric member having a skirt projecting downwardly from the lower face thereof within said sheltered space, and means for protecting the surface of said dielectric member within said downwardly projecting skirt from contamination and for preventing electrical discharge from said pin, said means comprising a sheet metal baffle secured to and electrically connected with said pin and extending radially therefrom and forming a circumferential groove registering with the lower edge of said skirt and providing a flux control ring at the outer edge 35 of said groove for preventing concentration of electrostatic stress emanating from said pin.

5. An insulator comprising a dielectric member having a recess therein, a pin having one end secured in said recess, a cap secured to said dielectric member for supporting said insulator, said dielectric member having an outwardly and downwardly extending flange thereon enclosing a sheltered space about the lower end of said pin, a pair of radially spaced circumferential skirts extending downwardly from the lower face of said flange, a sheet metal baffle secured in said pin and extending radially therefrom, said baffle having a circumferential groove in its upper face registering with the innermost one of said skirts, the outer edge of said baffle extending into the opening between said skirts, said baffle having a drainage opening therethrough at the bottom of said groove, and a supplemental baffle plate for breaking up air currents through 50 said drainage opening.

6. An insulator comprising a dielectric body having a radially extending flange, a fitting projecting downwardly from the lower side of said body and a combined flux control and baffle 60 formed of conducting material and secured to and electrically connected with said fitting and projecting radially beneath said flange, the upper surface of said baffle and the lower surface of said flange having overlapping portions forming a labyrinthine passage from the outer atmosphere to the portion of said dielectric member adjacent said fitting, the outer edge of said baffle constituting a flux control ring for diffusing the electrostatic flux of said fitting and preventing concentration of said flux and attendant electrical discharge from said fitting.
